UNITED STATES PATENT OFFICE

CHARLES H. CROWELL, OF FAIRVILLE, PENNSYLVANIA

APPARATUS FOR TENSIONING AND SMOOTHING TEXTILES

Application filed July 7, 1927. Serial No. 203,894.

The invention relates in general to methods and apparatus for treating cloth and, more particularly, to a process and apparatus for tensioning smoothing, stretching and spreading a web of fabric prior to further treatment.

- 5 According to the invention a suitable guide roll is provided which may have a rough surface over which the web of cloth is passed. One or more spreading rolls are provided over which the web is passed after being passed over the guide roll, the spreading rolls operating to smooth out the wrinkles, provide the tension necessary for subsequent processing and laterally spread and stretch the web.
- 10 10 The guide roll and spreading rolls may be mounted in a suitable frame and the spreading rolls may be built in sections, one or more sections being used as the occasion demands. Each spreading roll may be made up of a shaft on which are detachably mounted sleeves having suitable threads cut therein to exert the desired spreading action and tension on the web.
- 15 15 The guide roll and spreading rolls may be mounted in a suitable frame and the spreading rolls may be built in sections, one or more sections being used as the occasion demands. Each spreading roll may be made up of a shaft on which are detachably mounted sleeves having suitable threads cut therein to exert the desired spreading action and tension on the web.

20 20 Various other features and advantages of the invention will be apparent from the following particular description and from an inspection of the accompanying drawings.

25 25 Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which,

30 30 Fig. 1 is a more or less diagrammatic view of one form of apparatus with which the invention may be practiced;

35 35 Fig. 2 is a detail showing one form the sections of spreading rolls may take and illustrating how the sections are fitted together;

40 40 Fig. 3 is a section taken on the line 3-3 of Fig. 2, illustrating the construction of the spreading rolls and section;

45 45 Fig. 4 is a section on the line 4-4 of Fig. 3;

50 50 Fig. 5 is a detail further illustrating the construction of the spreading rolls; and

55 55 Fig. 6 is a modification showing a different

shape the sections may take so that they may be easily fitted together.

In the following description and in the claims parts will be identified by specific names for convenience, but they are intended to be as generic in their application to similar parts as the art will permit.

60 Like reference characters denote like parts in the several figures of the drawings.

65 Referring now to Fig. 1, one form of apparatus for practicing the invention is shown for purposes of illustration. Although there is shown a roll on which the cloth is packed and a particular form of treating rolls, it will be understood that the invention may be used with cloth packed in any way such as in bales and also with any kind of treating apparatus.

70 70 In Fig. 1 the apparatus as shown comprises a suitable frame A in which is journaled the several rolls for performing the various functions. The apparatus comprises a suitable bundle roll 1, on which the web 2 of goods, which may be open mesh gray goods, is rolled, this bundle roll being disposed on a suitable shaft 3, the shaft being mounted in suitable guides 4 so that the surface of the roll always rests against the adjoining guide roll 5.

75 75 The guide roll 5 comprises a suitable cylinder suitably journaled in the frame, and its surface 6 may be sanded or otherwise roughened in any desired manner.

80 80 Also suitably mounted in the frame A is a single section 7 of spreading rolls. Referring more particularly to Figs. 1, 3, 4 and 5, this section comprises end plates 8 suitably held together by rods 9, and three spreading rolls 10, these rolls being suitably journaled in the end plates 8. Each roll has a gear 13 overhung on its shaft meshing with the gear on the adjoining shaft. The two lower rolls 90 are arranged in a horizontal plane and the upper roll is arranged perpendicular to a line joining the centers of the lower shafts and midway between the two lower rolls.

85 85 Each spreading roll 10 is made up of a shaft 95 having an enlarged mandrel or drum portion 15 through the middle part of which a pin 16 is provided, the ends of the drum 15 being suitably threaded. Detachably telescoped upon the drum 15 is a pair of sleeves 100

17, each sleeve having notches 18 at its end to engage the pin. Suitable nuts 19 having openings 20 therein so that they may be turned are threaded on threaded portions to hold the sleeves 17 against the pin 16 to prevent relative rotation between the sleeves 17 and the drum 15.

18 Each sleeve 17 is provided with a suitable helical thread 21, the thread on one sleeve being right-handed and the thread on the other 19 being left-handed. The thread is shown as V-shaped in cross section, the side 24 of the thread facing the end of the roll being substantially perpendicular to the axis of the roll, and the other side 25 making an angle of 45 15 degrees therewith.

20 Suitably journaled in the frame are subsequent treating rolls comprising the smaller rolls 26 and the larger rolls 27, the uppermost roll being a winding roll 28 upon which the treated fabric is wound. These treating rolls may be either dyeing or filling rolls, or 25 may be used to give any desired treatment whatsoever. It will be understood that suitable sources of aqueous dyeing or filling mixture are provided for treating the web.

25 In case the single section 7 of spreading rolls shown in Fig. 1 is not sufficient, a plurality of sections 7 of spreading rolls may be used, as shown in Fig. 2. The end plates 8 30 are generally triangular, and the plates may be fitted together as shown in Fig. 2, with the gear 13 of each roll meshing the next gear of the chain.

35 In some cases it may be preferable to make sections of spreading rolls as shown in Fig. 6. In this modification each section 29 comprises a group of four rolls 10 arranged at the corners of a rhomboid or diamond, the rolls being journaled in end plates 30 of similar 40 shape. Each roll 10 is equally spaced from its immediately adjoining roll so that they can be driven by gears in the same manner as described in connection with Fig. 2. The 45 sections are disposed as shown in Fig. 6, and any number may be used to give the desired action.

50 As shown in Fig. 1, the bundle roll 1 contacts the guide roll 5 so that the guide roll in rotating in the direction indicated, operates as a surface unwinder of the bundle roll. The several treating rolls 26 and 27 are shown maintaining substantial contact with each other and with the last spreading roll 10 so 55 that each portion of the web has continuous rigid support throughout its treatment by the treating rolls, thus preventing shrinkage of the web. In other words, there is no space between adjoining treating rolls where the web 60 unsupported may be allowed to shrink.

It will be understood that suitable driving devices are provided to drive the several rolls, the guide roll 5 being driven in the direction of web travel, and as indicated by the arrow. 65 The spreading rolls 10 are preferably driven

in the opposite direction to that of web travel as indicated by the arrows to properly tension the web for its subsequent processing. In some cases it may be desirable to have the spreading rolls rotate in the same direction as web travel. It will be understood that the direction of the threads is so arranged that, when the web is drawn across the rolls, the threads will exert a spreading action, stretching the cloth and smoothing out the wrinkles. Furthermore, any number of stretching rolls may be used to give the desired action, and the pitch of the threads may be changed and the rolls run at different speeds to provide the desired effect.

80 The provision of the guide roll allows the lateral position of the fabric to be controlled nicely. The guide roll prevents any side movement of the fabric which might otherwise occur due to the web slipping over on to one side of the spreading rolls, so that it receives more action from the thread sleeves on one side than on the other.

85 The turning of the spreading rolls against the travel of the web produces a tension on the web and at the same time it holds the woof or cross threads perfectly straight, smoothing out all wrinkles and expanding the web to full normal width. This prevents any extra strain on the selvage edges and consequent bow shaping of the cross threads which might otherwise be caused by providing the necessary tension for processing the web.

90 The combination of the spreading rolls and guide roll operates to give increased yardage without any drawing together or narrowing of the web and when used with the treating rolls which prevent shrinkage, the entire organization produces a superior product of 95 maximum yardage.

95 Although certain novel features of the invention have been shown and described and are pointed out in the annexed claims, it will be understood that various omissions, substitutions and changes in the form and details of the apparatus illustrated may be made by those skilled in the art without departing 100 from the spirit of the invention.

105 What is claimed is:—

110 1. In combination, a plurality of treating rolls arranged in an upper and lower layer, the rolls in one layer being staggered with respect to those in the other layer, said rolls being adapted to carry a web zig-zag back and forth between said layers, each roll having a gear, said gears each meshing the gears of its adjoining rolls, said rolls being grouped into like sections, each section having its own bearing plates, said bearing plates and sections fitting together, whereby any desired 115 number of sections may be used according to requirements.

120 2. In apparatus for treating an open mesh cloth web, a spreading roll having oppositely 125 requirements.

130

inclined helical spreading elements thereon,
a guide roll immediately preceding said
spreading roll and in substantial contact
therewith, said guide roll having a guiding
surface extending the entire working portion
of the roll so that each portion of the open
mesh web across the web is effectively guided
onto said spreading roll, and means for feed-
ing said web from said guide roll directly onto
said spreading roll.

10 In testimony whereof I have hereunto set
my hand.

CHARLES H. CROWELL.
